James D. Hamilton

UNITED STATES PATENT OFFICE.

WILLIAM C. KIRCHHOFF, OF RUSSELL, KANSAS, ASSIGNOR OF ONE-THIRD TO C. BRECKINBRIDGE AMYX AND ONE-THIRD TO JOHN WALTER POWELL, OF CHANUTE, KANSAS.

OIL-BURNER.

No. 893,172.

Specification of Letters Patent.

Patented July 14, 1908.

Application filed May 23, 1907. Serial No. 375,226.

To all whom it may concern:

Be it known that I, WILLIAM C. KIRCHHOFF, a citizen of the United States, residing at Russell, in the county of Russell and 5 State of Kansas, have invented certain new and useful Improvements in Oil-Burners, of which the following is a specification, reference being had to the accompanying drawings.

- 10 My invention relates to improvements in oil burners, and particularly to oil burners adapted for use with crude oil as a fuel; and an object of my invention is to provide an oil burner of this character which will be 15 simple in construction, cheap in manufacture and efficient in operation and which will produce perfect combustion of the oil, with the result that crude oil will become a cheap and perfect fuel.
- 20 In the drawings illustrating the principle of my invention and the best mode now known to me of applying that principle, Figure 1 is a central vertical section of my new oil burner; Fig. 2 is a section and Fig. 3 is a 25 sectional detail showing the damper.

Upon the top of the base *a* is mounted the conical wall *b* of the combustion chamber *c*. The conical wall *b* is provided near its top with a rim or flange *d* which supports the 30 drum *e*. The latter in turn supports the top *f* formed with the holes *g* and a central pipe *h* in which is mounted a pipe *k* formed with outwardly flaring walls *m* at its lower end. These flaring walls direct the flame and heat 35 into the parts below them and cause in this way better combustion of the fuel which may find its way into such parts. Over the upper end of the pipe *k* is slipped the cap *h'* to the top *n* of which is secured a chain *o* 40 which extends down through the pipe *k* into the tube *p* seated in the fire-pot *q* in the combustion chamber *c*. In the pipe *k* are formed holes *r* and between the cap *h'* and the pipe *h* is mounted a circular damper or 45 air valve *s* formed with holes adapted to register with the holes *r* when the damper *s* is turned, thereby controlling admission of air to the pipe *k*. The tube *p* is formed with openings *t* at its lower end.

50 The oil trickles down the chain *o* into the

tube *p* and is heated in its descent through the pipe *k* by the heat from the walls thereof. The air entering through the holes in the damper *s* and the holes *r* in the pipe *k* flows down through the pipe *k* and expands upon 55 issuing from the mouth *m*. Further, the air entering through the openings *t* in the lower end of the tube *p* flows upwardly burning any of the oil which has trickled down to the lower end of the chain *o*. Thus, two flames 60 are created, one ascending and the other descending; and these two flames meet midway between the mouth *m* and the upper end of the tube *p* and an intense heat is created with the result that all the oil is converted 65 into vapor and consumed.

I claim:—

1. In an oil burner, the combination of a suitable source for the supply of oil; a pipe connected with said source and formed with 70 an aperture for the admission of air at its upper end and having downwardly diverging walls at its lower end; a chain which extends into said pipe and down which the oil trickles; a tube located below said downwardly 75 diverging walls and formed with openings in its lower edge, said tube being open at its end opposed to said walls; and a casing having a closed bottom upon which the lower edge of said tube is supported. 80

2. In an oil burner, the combination of a suitable source for the supply of oil; a pipe connected at one end with said source and formed with apertures for the admission of air, the other end of said pipe being formed 85 with downwardly diverging walls; a chain which extends through said pipe and down which the oil trickles; a tube which is formed with openings at one end and into which said chain extends, said tube being located below 90 said flaring walls; and a fire-pot in which said tube is mounted.

3. In an oil-burner, the combination of a casing; a fire-pot mounted within said casing; a tube the lower edge of which is formed 95 with openings and rests upon the bottom of said fire-pot, said tube having its upper end open; means for leading the fuel to said tube; means for admitting air to the top of said casing; and means for directing air 100

upon the outside of said tube, the air entering said tube through the openings in its lower edge and passing thence upwardly through said tube, and the upper end of the 5 latter being separated by an interval from the last-named means.

In testimony whereof I have hereunto set

my hand at said Russell this 17th day of May, A. D. 1907, in the presence of the two undersigned witnesses.

WILLIAM C. KIRCHHOFF.
